(57) **CLAIM**

The ornamental design for a garden planting box, as shown and described.

DESCRIPTION

FIG. 1 is a perspective view of a garden planting box showing my new design;

FIG. 2 is a front view thereof, a rear view being a mirror image of the front view;

FIG. 3 is a left side view thereof, a right side view being a mirror image of the left side view;

FIG. 4 is a top view thereof, a bottom view being a mirror image of the top view; and,

FIG. 5 is a partially enlarged view showing the area 5 in FIG. 1.

The broken lines indicating an enlargement portion of the design form no part of the claimed design.

1 Claim, 5 Drawing Sheets
